The ornamental design for a mount for securing a sighting device to a firearm, as shown and described.

DESCRIPTION

The present design is for a device used to mount a sighting device such as a laser sight or flashlight to a weapon such as a shotgun.

FIG. 1 is a perspective view of a mount for securing a sighting device to a firearm showing a preferred form of my new design;

FIG. 2 is a side elevation view thereof, the opposite side being a mirror image;

FIG. 3 is a top plan view thereof;

FIG. 4 is a bottom plan view thereof;

FIG. 5 is an end elevation view as viewed from the left in FIG. 2; and,

FIG. 6 is an end elevation view as viewed from the right in FIG. 2.
